UNITED STATES PATENT OFFICE.

WILLIAM P. BOOTH, OF SOUTH BEND, INDIANA, ASSIGNOR OF ONE-HALF
TO THE SOUTH BEND TELEPHONE COMPANY, OF SAME PLACE.

TERMINAL FOR ELECTRIC CONDUCTORS.

SPECIFICATION forming part of Letters Patent No. 594,932, dated December 7, 1897.

Application filed December 16, 1896. Serial No. 616,087. (No model.)

To all whom it may concern:

Be it known that I, WILLIAM P. BOOTH, a citizen of the United States, residing at South Bend, in the county of St. Joseph and State of Indiana, have invented certain new and useful Improvements in Terminals for Electrical Conductors, of which the following is a specification.

My invention relates to that class of devices used in telephone, telegraph, electric-light, power, signaling or other like systems to protect the ends of conductors entering the same whether singly or grouped in the form of a cable.

For the purposes of illustration I have selected that class of devices used in telegraph and telephone offices. In these systems it has been customary to employ terminals merely as a means of shielding the ends of conductors. The necessary testing arrangements, fuses, and lightning-arresters have been placed either on the distributing-board or on the switchboard. This scatters the testing and protecting devices, causing inconvenience in locating trouble and making repairs. Heretofore these terminals have been secured to walls or partitions, rendering one of their sides useless.

The objects of my improvements are, first, to enable three sides of the terminal-head to be used for connections, the remaining side being removable; second, to enable the connections to be reached from all sides of the terminal; third, to provide by one device for the protection of the cable and a means of supporting the terminal-head and generally to make the testing and connecting of either the external or office circuits easier and quicker. I attain these objects by the mechanisms illustrated in the accompanying drawings, in which—

Figure 1 represents in projection the top part or head of the terminal; Fig. 2, a front view of the bottom part of the terminal, showing the hollow pedestal, which is represented as broken open in two places, the upper break showing the union of the cable with the nozzle of the head, the lower showing the cable alone; Fig. 3, a cross-section of head through line $x'y$ of Fig. 2; Fig. 4, a plan view of the new multiple plug used in connection with

the resilient strips 6 and 7 or angular plates 8 and 9; Fig. 5, a side view of Fig. 4; Fig. 6, a cross-section of Fig. 4 through the line $v'w$.

References 1 1 1 represent the three sides 55 of the cast-iron head 11; 2, the removable cover; 3, sheets of insulation secured to two sides of the box; 4, lightning-conductors insulated from the body of the head; 5, a metallic strip connecting the lightning-conductors 60 with the earth; 6 and 7, resilient strips of conducting material; 8 and 9, angular plates connecting the resilient strips with fuses; 10, fuse-terminals; 11, fuses; 12, metallic rods bushed with insulating material 13; 14 and 65 15, cable-wires leading from lead-covered cable 16; 17, a nozzle forming a part of the head through which cable 16 enters the head; 18, a hollow standard protecting cable; 20, a base on which is mounted the hollow standard 70 18; 27, a fastening-flange surmounting the hollow standard 18 and adapted to be secured to the bottom of the head; 19, insulating material forming the body of multiple contact-plug; 20, raised portion serving as a 75 guide for same; 21 and 22, conducting-contacts serving to connect 6 and 7 with the usual test instruments at end of wires 23 23; 24 and 25, wires leading from terminal to distributing-board or switchboard. 80

In Fig. 1 the resilient strips 6 and 7 are ordinarily in contact with electrodes 8 and 9. The wires going to the distributing-board and station instruments connect at 24 and 25.

The resilient strips 6 and 7 operate in pairs 85 if a double or "metallic" circuit is used; but in case my terminal is employed in connection with single or "grounded" circuits a single plug having one side of conducting and the other of insulating material may be used to 90 connect with one side of testing apparatus, the circuit being completed by connection to earth of the other side of said apparatus, or a plug having two sides of conducting material with their transverse surfaces diametrically opposite and separated by insulation will 95 serve to introduce into the circuit the testing apparatus.

The usual method of testing has been to disconnect the station-wires from a metallic rod 100 similar to 12. (Shown in cross-section in Fig. 3.) The frequent disconnection of these

conductors is an inconvenience as well as a damage to the ends of the conductors themselves, but by using plugs in connection with the resilient strips 6 and 7 and plates 8 and 9 the operation is quickened and much better performed. The circuit continues through the fuse 11 and reaches the cable-wires on the inside of the head by conductor 12. In case of lightning or other dangerous currents coming into the circuit the station apparatus is protected by lightning-arrester 4 and cut-out 11.

My new multiple contact-plug is used to connect with both sides of either the office or external circuits with one insertion, accordingly as the contacts 21 and 22 are placed toward or away from 6 and 7. It is made of insulating material faced with contacts of conducting material. It can be made with plane surfaces, but a better way is to provide one or more guides, either upon the plug or head, by making corresponding projections or depressions upon their respective surfaces. Figs. 4, 5, and 6 illustrate a good form of construction.

My hollow pedestal 18, 26, and 27 serves the four purposes of enabling the head to be placed at a convenient distance above the floor, of placing it at such a sufficient distance from the wall or partition that it can be reached from all sides, of being a support for it when so placed, and of providing a means of securing protection to the cable before it enters the head.

The method of using my pedestal is to bring the conductors or cable through an aperture in the floor, then thread them through the support 18 and nozzle 17 into the head, where the conductors are finally joined to posts 12. After connections are made the pedestal and head are united by bolts at fastening-flange 27 and the slack conductors or cable drawn tight from below. The base 26 is then screwed fast to the floor. If the pedestal is of proper height, a man of average size without changing the position of his body can reach the connections at the top or bottom of the longest terminal-head.

It will be understood that if the terminal is mounted upon a pole or upon the outside wall of a building the floor of a projecting and sustaining platform and the side of the pole or wall to which it is attached are analogous to the floor and wall of office herein mentioned; also, the line wires and cables protected out of doors is a parallel case to that of cables and switchboards indoors.

Although I have described more or less pre-

cise forms and details of construction, I do not intend to be understood as limiting myself thereto, as I contemplate changes in form, proportion of parts, and substitution of equivalents as circumstances may suggest or render expedient without departing from the spirit and scope of my invention and claims.

I claim—

1. In combination with a pair of resilient conducting-strips, and electrodes contacted thereby, a plug having multiple contacts of conducting material mounted on one side of a body of insulating material and adapted to form a connection between the pair of resilient strips or electrodes to test either the incoming or outgoing circuits.

2. In combination with a pair of resilient conducting-strips, a plug consisting of a body of insulating material having on one side multiple contacts, and means to guide the plug as it is inserted under or withdrawn from the said strips.

3. In combination with a system of electrical conductors terminated in a head, resilient conducting-strips, electrodes attached to said head and contacted by the strips and a plug having multiple contacts mounted on one side of a body of insulating material and adapted to be inserted between a pair of electrodes or strips to connect the testing instruments either with the electrodes or strips accordingly as the plug is inserted one way or the other.

4. As a new article of manufacture a plug having multiple conducting-contacts mounted on one side of a body of insulating material and adapted to be inserted between resilient conducting-strips and electrodes.

5. As a new article of manufacture a multiple plug said plug consisting on one side of insulating material and on the other of multiple contacts of conducting material and means to guide the plug as it is inserted under or withdrawn from resilient conducting-strips.

6. A multiple plug consisting of an insulating-body 19, raised portion 20 and contacts 21 and 22.

7. In combination with the hollow supporting-pedestal consisting of base 26, standard 18, and fastening-flange 27, of the terminal-head H, the nozzle 17 extending therefrom and to which is secured the cable 16.

WILLIAM P. BOOTH.
